Application March 2, 1943, Serial No. 477,755

4 Claims. (Cl. 20—101)

1

The present invention relates to the placement of particles of thermal insulating material to build up a thermally insulating integrated mass of such material in a confined space. In particular it relates to carrying the material in a gaseous vehicle (hereinafter referred to as air) to a deposited growing mass of such particles formed by deposition of particles from the vehicle.

In its general aspect, the invention contemplates completely confining a space to be so filled with insulation material, whereby to define the form of the mass to be produced. The space may be provided substantially completely by or within existing articles. However, as required or desired for the purposes of the invention, the space to be filled is completely defined by bounding facial walls having essentially some filtering area for exhausting the gas in which particles of the insulating material are introduced, and having essentially in the area of the confining walls one or more inlet areas for introducing the gas containing the particles, each such inlet area being essentially in and a fraction of a confining wall or face in a manner analogous to the relation of the area of a pouring sprue in molds for casting metal articles to a space-defining area of the mold.

It is also a general aspect of the invention that the particles of insulating material are such as may be consolidated into a gas-filtering body, when in finally deposited form, whereby in conducting and completing the introduction, gas entering the space through inlet area may pass through all or a part of the body as required to exhaust through filtering area.

Another general aspect of the invention permits the form of the space to be complex, or angular, and not limited to panel-form spaces. Thus, the vehicular stream of gas is introduced at a differential pressure, relative to the pressures at inlet area and at filtering area, and at such a velocity that the particles suspended in the gas are carried with turbulence inside the space to all portions of the space remote from inlet area, and that the differential pressure packs the deposited mass to a consolidated body filling the space while said pressure of the gas stream is maintained to and, if desired, even after the complete filling of the space.

The invention is applicable in many fields, for example in packing fiber or other insulating material into carboys to protect and insulate the flasks of liquid therein. However, its presently preferred use is in insulating the doors and cabinets of refrigerators, such as are used in homes.

In the field of artificial refrigeration, high

2

standards for insulation in domestic and other refrigerators have developed in order to minimize heat loss, because high heat loss adds to the cost of operation. Considerable difficulty has been encountered in the commercial development of refrigerator insulation in parallel with the development of domestic artificial refrigeration. Along with high standards and for low heat loss, low cost of insulating material and of insulating process are important, as are uniformity in each cabinet, and uniformity from cabinet to cabinet in a production line.

In addition, there is the problem of permanence, in which resistance to settling of packed bulk insulation is most important. Such resistance can be attained by increasing the density of packing, with which heat leak or heat conductance increases, as a general rule, in the ranges encountered in refrigerators. It is, therefore, important to minimize density, consistently with acceptable resistance to settling and acceptable insulating value. All these factors lead to a need for a process which is subject to control for meeting them.

25 In the prior art there has been no low-cost process for packing a specified material uniformly and integrally into a cabinet, and uniformly from cabinet to cabinet in a production line. The present invention provides such a process, and so used it gives reproducible results with any reproducible material. Vegetable fibers such as from wood may readily be produced from time to time with reproducible properties within given specifications, and with such material and with the present invention, a low-cost process for uniformly and efficiently insulating spaces, such as those in refrigerators, becomes available to the manufacturers of refrigerators. Reference is made to my copending application Serial No. 336-30 495, filed May 22, 1940, now Patent No. 2,325,055, issued July 7, 1943, describing reproducible fibers, which are useful as particles for practice of the present invention.

The present invention is a continuation-in-part 45 of my prior application Serial No. 294,212, filed September 9, 1939, wherein the principles of the process are disclosed, which application is generic to the present application. The parent application Serial No. 294,212 is generic to Serial Nos. 477,751, 477,752 and the instant application, all filed March 2, 1943, as continuations-in-part of said parent application. In the series of applications: Serial Nos. 294,212, 477,751, 477,752 and the instant application Serial No. 477,755, the invention being claimed in each application is

generic to the inventions being claimed in each later serial number of the series.

It is an object of the present invention to insulate a confined space having two separated confining walls, by introducing into one of said walls at an inlet area therein a stream of gas carrying insulating particles, while filtering said gas from said space through both of said separated walls.

It is a particular object of the invention to insulate a refrigerator cabinet having a door opening in which cabinet there is mounted a food compartment, where there is an opening in one or in both of the cabinet and food compartment to accommodate the insertion into the food compartment of a refrigerator unit, by introducing a stream of gas into the space to be insulated by way of a portion thereof in the vicinity of the said door opening, while exhausting said gas through filtering areas in the vicinity of the door opening and at one or both of said openings for the unit.

Various other and ancillary objects and advantages of the invention will become apparent from the following description and explanation of the invention given with reference to the accompanying drawings, in which:

Fig. 1 represents a refrigerator cabinet with its food compartment mounted therein, the cabinet being shown lying horizontally on its back; and showing also a screened opening at the back wall of the food compartment;

Fig. 2 illustrates a side elevation of a fixture, shown also in Fig. 3, which fixture is placed over the space between the food compartment and the cabinet at the door opening of the cabinet before the breaker strip closure for said space is applied;

Fig. 3 is a view similar to Fig. 1 showing the fixture of Fig. 2 in place over the cabinet;

Fig. 4 is a simplified cross-section of the cabinet shown in Fig. 1 illustrating opposed openings in the walls of the cabinet and the food compartment, and illustrating a filtering screen in the food compartment opening and a closure plate in the cabinet opening;

Fig. 5 is a view similar to Fig. 4 showing the positions of the closure plate and filtering screen reversed from the position of Fig. 4;

Fig. 6 is a view similar to Figs. 4 and 5 showing both of said openings containing filtering screen; and

Fig. 7 represents a blower and feeding means therefor which is connected to the fixture of Fig. 2.

In my earlier parent application Serial No. 294,212, the process is described generically and specifically with respect to various forms of the space to be filled, and various types of space-confining walls, and removable fixtures, having particular reference to variations in the process for insulating domestic type refrigerators. These variations include filling a refrigerator in which the food compartment is already mounted, and also in which the food compartment is not mounted. In the latter case, a fixture in the form of a dummy for the food compartment is employed, and the fixture is used to provide filtering area, and may be used to provide inlet area. The process is flexible for accommodating it to various types of refrigerators, as well as various types of spaces not necessarily those of refrigerators. In the said earlier application there is claimed specifically a method of filling a refrigerator in which the food compartment is mounted, both the cabinet and the food compartment

ment having openings therein for accommodating the insertion into the food compartment of a refrigerating unit. One of the said openings to the space is used for introducing the gas, while the other is blocked off. The open space at the door opening between the cabinet and the food compartment, where breaker-strip material is located in the completed refrigerator, is closed by a fixture or closure provided with filtering area, and preferably including also some imperforate area. Thus, the gas introduced passes through the gas-filtering body of insulating material built up in the space. Then the fixture is removed, and breaker strip used to close the gap. The space between the openings for the unit thus has insulation, which may be disturbed as necessary in making connections when installing the refrigerating unit.

It is also set forth that the stream is introduced at a differential pressure between inlet and filter areas. This may be effected by having atmospheric pressure at either the inlet area, or at the filtering area. The latter is preferred for many practical and mechanical reasons.

In the present application it is likewise intended that the pressure be a differential one, but to simplify the description and the illustration, only the preferred one of super-atmospheric pressure at inlet area is specifically described and illustrated without intention to limit the invention thereto.

After the introduction of the insulating material into the space to be insulated, especially in a refrigerator, there are numerous mechanical operations which may be necessary to complete the article for use or sale. However, these form no essential part of the invention, and detailed description and illustration of them are herein omitted.

The preferred closures or other means having filtering area are preferably permanent fixtures used in a production line, and are in preferred practice removed after each use. However, these may be of other structure, for example, metal or cloth filters of such character that they need not be removed. When retained, they may be a permanent part of the final structure, covered or not. Hence, the removal of such closures is not considered an essential part of the process. But in certain cases it may be included as an essential part of certain aspects or variations of the invention.

The present invention may be used for fibers, flakes and particles of other forms. Examples of fibers are hair, wood fiber, vegetable fiber, kapok, mineral wool, glass wool, asbestos, straw, grasses and many others. Examples of other materials are flaked paper, exfoliated vermiculite, mica, ground cork and like materials. Fibers are preferred, because they mat and felt and produce stable forms in more complex variations of the invention where fixtures may be used and removed. The following illustrations are therefore given with respect to wood fiber, such as that according to my said copending application Serial No. 336,495, filed May 22, 1940, Patent No. 2,325,055, granted July 27, 1943, which were developed primarily for use in the present invention.

The invention involves the building up of a consolidated gas-filtering body of particles of insulating material introduced as suspended matter in a stream of gas, into a confined space to be insulated; and it involves the provision in the confining walls of said space of filtering area

to retain the particles and exhaust the gas. The location of inlet area, the number of inlet areas, and the location, size and number of filtering areas are not critical with respect to any given space. This is because the stream of gas is introduced at a velocity to impel the particles with turbulence into the space and to all parts of the space. The greater the shortest distance from inlet area to filtering area, the thicker is the body of insulating material through which gas must pass to exhaust. Therefore, for practical convenience, it is desirable to have filtering area close to, or even adjacent to inlet area. Experience has shown that, because of the turbulence, the particles may deposit in regions some of which are adjacent to filtering area, and others of which are remote from both inlet area and filtering area. The resulting deposit grows toward the inlet area, and to or through the inlet area. In such case the filtering area close to or adjacent inlet area facilitates the deposition of the last-deposited material. The conditions establish a complexity of air currents which change as the remaining space to be filled changes. Cyclonic currents have been observed which tend to throw carried particles centrifugally out of the local air stream and deposit them by centrifugal force and in the manner described. Also direct deposition by filtration has been observed as one of the resulting actions to deposit the introduced particles.

In my said earlier application Serial No. 294,212, I have disclosed the filling of a refrigerator cabinet in which is mounted a food compartment, by use of a fixture closure over a peripheral area at the door-opening of the cabinet, which area communicates with the space to be insulated between the cabinet and the food compartment. Where there are openings in the food compartment and the cabinet to accommodate the insertion into the food compartment of a refrigerating unit, as disclosed therein, one or both of said openings may be closed, or may have filtering area.

According to the present invention, one or both of these openings have filtering area in such practice. The case where such openings, if they exist, are closed is described and claimed generically in my coiled application Serial No. 477,751, and specifically in my coiled application Serial No. 477,752, each of which applications is generic to the present application.

Fig. 1 represents in plan view a conventional refrigerator cabinet 10 lying on its back. There is a door opening at the top. The cabinet shell, when of metal, has a peripheral internal flange 11, across corners of which braces 12 are secured. A food compartment 13 is mounted inside the cabinet by means of an external flange 14 thereon, secured to said braces 12. This forms a space 15 around the food compartment, and under it (in the position shown), to receive insulation. In the back of the food compartment is illustrated a wire screen 16 suitably closing an opening in the food compartment which is provided for use in connection with a refrigerating unit, said screen serving as a wall to confine said space 15, and providing filtering area in such space-confining wall.

In the finished refrigerator, breaker-strip material, shown in fragmentary form at 17, covers the open space at the door opening, this being suitably secured as to the flanges 11 and 14. A cover plate is shown in part at 18, for the bottom front of the operating refrigerator, be-

hind which operating machinery is located. A screened opening 19 (Fig. 1) in the bottom rear of the cabinet space to be insulated may be present, the hole serving for connections from the operating machinery to the refrigerating unit, and the screen serving as filtering area.

The peripheral open space 15 at the door opening is covered by a temporary closure, or fixture shown in Figs. 2 and 3. The closure comprises a frame of members 20 fitting over flange 14, and a frame of members 21 fitting over flange 11 with space between the frames. At the corners, this space may be, and is, covered with means 23 providing imperforate area, also confining said space 15. Adjacent the corners are screens 24 providing filtering area for confining said space 15. Between the pairs of screens on each panel side of space 15, there is inlet area 25. Directly over the inlet areas 25 there are provided hoods 26 to 29 which are connected by conduits 30 to a common unit 31 into which the air stream is blown. Hoods 28 and 29 may be bifurcated internally as shown. Windows 32 permit seeing when fiber or the like packs into the hoods, indicating completion of the filling of space 15.

As illustrated in Fig. 4, which is a diagrammatic cross-section on line 4-4 of Fig. 1, there is an opening in the cabinet 10 opposite the screen 16, which opening in the cabinet is shown closed by a plate or other means 35, which may be the surface of a platform on which the back of the cabinet lies.

Fig. 5 is a modification of the arrangement already described, in form similar to that of Fig. 4, in which a screen 36 closes the opening in the cabinet, and a plate 37 closes the opening in the food compartment 13.

Fig. 6 is a modification of the two above arrangements, in form similar to that of Figs. 4 and 5, in which screens 38 and 39 close the openings respectively of the cabinet 10 and food compartment 13.

Fig. 7 shows a blower system to which the common unit 31 (Figs. 2 and 3) may be connected. A fan-type blower 45 has pipe 46 for the entry of air, into which fiber may be fed by hand, or by a mechanical device, such as a picker, or a worm screw 46a. The fan discharges downwardly through conduit 47.

Consider the apparatus of Fig. 7 when the pipe 47 is 6 inches in diameter, and connected to a fixture for filling a space. The fan is operated at 3740 R. P. M. by a 15 H. P. motor of 1800 R. P. M. Running idle (connected and operated but no fiber fed), the measured pressures are as follows:

Table I

60	In pipe 47	Pressure in inches of water
Lateral (static) pressure.....		8.5
Total pressure.....		10.25
Velocity pressure.....		1.75
Velocity.....		5300 ft. per minute.
Output.....		1040 cu. ft. per minute.

The system shown in Fig. 7 has been used to fill a certain space $\frac{1}{4}$ full, then to $\frac{1}{2}$ full, then to $\frac{3}{4}$ full, and then to 100% full, with measurements of the system (idle) at each stage. The measured values are combined in Table II with values taken from Table I and are in the same units as those in Table I.

Table II

Measured in pipe 47	Empty	1/4 full	1/2 full	3/4 full	Full
Statis pressure	8.5	12	12	13.5	14.75
Total pressure	10.25	13	13	13.5	14.75
Velocity pressure	1.75	1	1	—	—
Velocity	5300	4006	4006	—	—
Output	1040	785	785	—	—

It is noted that under conditions where the exit is wholly or to a degree blocked, as when the space is full, there is a "back pressure" encountered at the inlet to the centrifugal fan.

The back-pressure is an important feature of the use of super-atmospheric pressure feed, with apparatus permitting back pressure. Consider in Fig. 1, that the fan may run while the feed line 41 is open. A momentum is established into pipe 47. As this is blocked off, the moving stream is retarded, at first in part, and fiber gradually fills up the inlet conduits. A window (later described) indicates this and the process may be stopped. If not stopped the back pressure at the inlet blows fiber back in pipe 46. Thus, fiber fed into the inlet will also be blown out the inlet. The appearance of back-feed or back-pressure is an indication of the final status of being filled.

Many factors influence the result, and practically, it is necessary to arrive at standard conditions for the particular equipment used, and the job at hand. For example, it has been found to be a general rule, that the faster the fiber is fed, the less the density of the mat obtained. However, this rule is limited to a very short period of time. In one test instance, the feeding time for the space was varied from fractions of a minute to several minutes. The curve of density has been plotted vertically against feeding time plotted horizontally. The curve rises rapidly, and at about 25 seconds it begins to flatten out. In about 60 seconds it has reached a maximum density. Such curves were obtained with different fan speeds, and it was found that high speeds (greater kinetic energy to fiber) at the same feeding time gave higher density mats. By constructing such curves from experimental procedure, the conditions for most efficient operation and for uniform operation, may be easily determined.

In operation of the arrangements described, with filtering area available at either or both of the openings for the refrigerating unit, the space is quickly filled, with exhaustion of air taking place at all the filtering areas. First, the vicinity of the screened unit opening fills by filtration, and the mass grows radially therefrom to the top fixture (of Fig. 2) where the major part of the air filters through the screens 24.

The use of a fan is preferred for the reason that it is a means of unfeeling the fibers to substantially individual fibers. It is this form which gives the best results. However, broadly, the fibers need not be completely unfeeling, and may be in clusters or small aggregates. Use of other means, such as vacuum on the screen end, or feeding fiber directly into a current of air, is conducive to providing such loose aggregates rather than individual particles of fiber. The important point is that these are not under mechanical pressure to felt them, and they tend to unfeel in process.

The terms "screening means" and "filtering area" as used herein or in the claims refer to an area with any effective lattice or perforated member which acts as a screen to filter particles from

the carrying gas, and it is to be distinguished from a member porous to air and from a crack or an elongated slot.

It is not essential that filtering area be limited to the unit-openings and the fixture described, and it may be located anywhere in the total area confining the space to be insulated. This is exemplified by the screened opening 19 in Fig. 1. The size and location of filtering area relative to inlet area, and the velocity of the stream of gas, are all such that particles are introduced with turbulence in all portions of the space to be insulated, and pack therein.

Numerous modifications and variations of the invention, not necessarily related to refrigerators, are contemplated as falling within the scope of the appended claims.

I claim:

1. In depositing particles of insulating material into the space defined and confined by walls including the walls of a refrigerator cabinet and of a food compartment mounted therein, and including removable closure means over said space at the door opening of the refrigerator, said closure means having a plurality of introductory inlets opening into said space including one to each panel-form space at the door opening, of which walls the space-confining surfaces include a major portion which is substantially resistant to the passage of gas and one or more remaining portions, each in the form of screening means with foramina relatively minute compared with said one or more inlets, for venting gas from said space and for retaining said particles in the space, of which screening means one is located in one of the back walls of said refrigerator, the method which comprises, suspending in a moving gas, particles of insulating material which pack to a consolidated body that is a gas-filtering body at an insulating density of the so-packed particles; introducing the resulting moving gaseous suspension into said space by conducting the suspension to and through said introductory inlets; simultaneously venting said gas from said space through said screening means, and thereby filtering said vented gas from particles, thereby depositing and packing particles to form a growing gas-filtering mass thereof in corresponding portions of said space over and extending away from said screening means; simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through said screening means and also through said growing mass at least until a body of said particles begins to form in each of said inlets and said space is completely packed with said particles consolidated to a gas-filtering body at an insulating density and resultingly molded into said space and compressed therein by the differential introduction pressure between said inlets and said screening means; removing said closure means and retaining in situ the material packed into said space; and applying a confining material over the open space left by removal of said closure means.
2. In depositing particles of insulating material into the space defined and confined by walls including the walls of a refrigerator cabinet and of a food compartment mounted therein, and in-

cluding removable closure means over said space at the door opening of the refrigerator, said closure means having a plurality of introductory inlets opening into said space, of which walls the space-confining surfaces include a major portion which is substantially resistant to the passage of gas and one or more remaining portions, each in the form of screening means with foramina relatively minute compared with said one or more inlets, for venting gas from said space and for retaining said particles in the space, of which screening means at least one is in said closure, and another is in one of the back walls of the refrigerator, the method which comprises, suspending in a moving gas, particles of insulating material which pack to a consolidated body that is a gas-filtering body at an insulating density of the so-packed particles; introducing the resulting moving gaseous suspension into said space by conducting the suspension to and through said introductory inlets; simultaneously venting said gas from said space through said screening means, and there filtering said vented gas from particles, thereby depositing and packing particles to form a growing gas-filtering mass thereof in corresponding portions of said space over and extending away from said screening means; simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through said screening means and also through said growing mass at least until a body of said particles begins to form in each of said inlets and said space is completely packed with said particles consolidated to a gas-filtering body at an insulating density and resultingly molded into said space and compressed therein by the differential introduction pressure between said inlets and said screening means; removing said closure means and retaining in situ the material packed into said space; and applying a confining material over the open space left by removal of said closure means.

3. In depositing particles of insulating material into the space defined and confined by walls including the walls of a refrigerator cabinet and of a food compartment mounted therein, and including removable closure means over said space at the door opening of the refrigerator, said closure means having a plurality of introductory inlets opening into said space including one to each panel-form space at the door opening, of which walls the space-confining surfaces include a major portion which is substantially resistant to the passage of gas and one or more remaining portions, each in the form of screening means with foramina relatively minute compared with said one or more inlets, for venting gas from said space and for retaining said particles in the space, of which screening means there are at least one in said closure means for each panel space at the door opening, and another in one of the back walls of the refrigerator, the method which comprises, suspending in a moving gas, particles of insulating material which pack to a consolidated body that is a gas-filtering body at an insulating density of the so-packed particles; introducing the resulting moving gaseous suspension into said space by conducting the suspension to and through said introductory inlets; simultaneously

venting said gas from said space through said screening means, and there filtering said vented gas from particles, thereby depositing and packing particles to form a growing gas-filtering mass thereof in corresponding portions of said space over and extending away from said screening means; simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through said screening means and also through said growing mass at least until a body of said particles begins to form in each of said inlets and said space is completely packed with said particles consolidated to a gas-filtering body at an insulating density and resultingly molded into said space and compressed therein by the differential introduction pressure between said inlets and said screening means; removing said closure means and retaining in situ the material packed into said space; and applying a confining material over the open space left by removal of said closure means.

4. In depositing particles of insulating material into the space defined and confined by walls including the rectangular walls of a refrigerator cabinet and of a rectangular food compartment mounted therein and including a removable closure over a rectangular space peripheral to the food compartment at the door opening of the refrigerator, said closure having four spaced introductory inlets opening into said peripheral space, of which walls the space-confining surfaces include a major portion which is substantially resistant to the passage of gas and one or more remaining portions, each in the form of screening means with foramina relatively minute compared with said four inlets, for venting gas from said space and for retaining said particles in the space, including screening means in said closure and screening means in one of the back walls of said refrigerator, the method which comprises, suspending in a moving gas, particles of insulating material which pack to a consolidated body that is a gas-filtering body at an insulating density of the so-packed particles; introducing the resulting moving gaseous suspension into said space by conducting the suspension to and through said introductory inlets; simultaneously venting said gas from said space through said screening means, and there filtering said vented gas from particles, thereby depositing and packing particles to form a growing gas-filtering mass thereof in corresponding portions of said space over and extending away from said screening means; simultaneously maintaining in the remaining portion of said space a condition of turbulence of said gaseous particle-suspension by maintaining a high and sufficient velocity therefor in introducing said suspension whereby the turbulence causes deposition and packing of particles in margins of the turbulent space; continuing said introduction, said maintenance of turbulence, and said venting of said gas through said screening means and also through said growing mass at least until a body of said particles begins to form in each of said inlets and said space is completely packed with said particles consolidated to a gas-filtering body at an insulating density and resultingly molded into said space

and compressed therein by the differential introduction pressure between said inlets and said screening means; removing said closure means and retaining in situ the material packed into said space; and applying a confining material over the peripheral space left by removal of said closure means.
